UNITED STATES PATENT OFFICE.

CLARENCE A. ROUSSEAU, OF RIVERSIDE, CALIFORNIA.

CHASE FOR PRINTERS' USE.

1,212,405.

Specification of Letters Patent. Patented Jan. 16, 1917.

Application filed June 21, 1916. Serial No. 104,879.

To all whom it may concern:

Be it known that I, CLARENCE A. ROUSSEAU, a citizen of the United States, residing at Riverside, in the county of Riverside and State of California, have invented certain new and useful Improvements in Chases for Printers' Use, of which the following is a specification.

The present invention relates to chases for printing presses, and more particularly to a chase wherein the page or set-up is automatically locked from the sides by means of pressure applied at one end in the usual manner.

The present invention constitutes an improvement on the printer's chase for which I have made application for United States Letters Patent under date of March 4, 1916, Serial No. 82213, and its principal object is similar to that set forth in said prior application, namely to do away with the necessity of employing the usual lock-up stick and quoins at the side of the chase, thereby reducing the width of the chase required for a set-up of given width, and enabling two or more pages to be simultaneously printed on a narrower sheet than when a chase of the ordinary type is employed, by cutting down the margin required between the adjacent pages.

The improvements constituting the present invention enable the chase to be locked up more quickly and more easily, for the reason that the side members, although movable relative to the end members, are at all times held in operative relation therewith. The only operation necessary, therefore, is to lock up the page from the end, in any well known manner, pressure being automatically applied to the sides at the same time.

With the above mentioned and other objects in view, the invention consists in the novel construction and combination of parts hereinafter described, illustrated in the accompanying drawings, and pointed out in the claims hereto appended; it being understood that various changes in the proportion, form, size and details of construction within the scope of the claims may be resorted to without departing from the spirit of the invention.

To more fully comprehend the invention, reference should be had to the accompanying drawings, wherein—

Figure 1 is a plan view of my chase, with a page locked up therein. Fig. 2 is an

enlarged detail plan, showing the construction of the inter-locking corners and the spring of the side members. Fig. 3 is an end elevation of the chase with my improved auxiliary clamp in position. Fig. 4 is a plan view of the same, portions of the chase being omitted. Fig. 5 is a detailed elevation, enlarged, of one of the inter-locking corners.

In the drawings, the reference numerals 1 designate the end members of the chase, and 2 the side members thereof. The two end members are similar in every respect, as are the two side members. Said end members are formed, at their ends, with projecting tongues 3 having inwardly inclined faces 4. The side members 2 are formed at their ends with laterally projecting tongues 5 having inwardly inclined faces 6, said tongues 3 and 5 interlocking, as shown in the drawings, to form a mortise joint.

At the ends of the end members 1, on the outer edges thereof, are fixed projecting locking plates 7, adapted to fit loosely within recesses 8 in the ends of the side members 2. Said locking plates 7 hold the end and side members in interlocking relation, while permitting a limited amount of movement at the joint. For this purpose the recesses 8 are deeper, as shown, than the thickness of the locking plates 7.

The side members 2 are preferably sprung inwardly at their central portions by approximately one sixty-fourth of an inch, in a chase fifteen inches in width, as shown in Fig. 2 of the drawings, where a—a are straight lines extended from the central portions of said side members. The object of this spring in the side members is to compensate for their elasticity to the extent of providing approximately equal lateral pressure on the set-up throughout its entire length.

In setting up a page within the chase, the end members 1 are first moved inwardly as far as the locking plates 7 will permit. In this position, the inclined faces 4 and 6 of the mortise tongues 3 and 5 permit the side members 2 to spread apart slightly. The type 9, Fig. 1, is then set up, occupying the full width of the chase, and making a snug fit between the side members 2. A foot stick 10 is then placed at one end of the page, and pressure applied thereto by any well known means, as, for example, by quoins 11. This

end pressure not only locks up the form end-
wise, but also, by spreading the end mem-
bers 1 to the outward limit of their play,
causes the inclined faces 4 and 6 of the
mortise tongues 3 and 5 to draw the side
members 2 together, thus exerting lateral
pressure as well. The form is thus auto-
matically locked up laterally by the pressure
applied at its end by the quoins 11.

10 To secure additional side pressure upon
the set-up, as a matter of precaution in han-
dling large and heavy forms and carrying
the same from the imposing stone to the
press, I provide an auxiliary clamp 12, Figs.
15 3 and 4 of the drawings, which is placed
transversely across the chase, at its central
portion, after the same has been locked up
as described above. One end 13 of said
20 clamp bears against one of the side members
2, and the other end 14 is spaced from the
other side member, to permit of the intro-
duction therebetween of a quoin 15. An
aperture 16 is formed in the bridge portion
25 of the clamp, so that a key 17 may be in-
serted therethrough to lock said quoin 15.
This clamp, it is understood, is removed
when the form is placed in the press.

Having thus described my invention,
what I claim as new and desire to protect
30 by Letters Patent is:—

1. A chase for printing presses comprising
end members, side members associated
therewith by means of inter-locking joints

having inclined co-operating faces, whereby
outward movement of said end members 35
causes inward movement of said side mem-
bers, and means for retaining said end mem-
bers and said side members in inter-locking
relation.

2. A chase for printing presses comprising
40 associated end and side members having
at their end portions inclined inter-locking
tongues adapted to unite said members in
movable relation one to the other, and means
45 for limiting the relative movement of said
members and for retaining the same in inter-
locking relation.

3. A chase for printing presses comprising
50 end members, side members bent in-
wardly at their central portions and associ-
ated in limited movable relation with said
end members by means of inter-locking
55 tongues having inclined faces, whereby out-
ward movement of said end members causes
inward movement of said side members, and
means for limiting the relative movement of
said members and for retaining the same
in inter-locking relation.

In testimony whereof I have signed my
name to this specification in the presence of
60 two subscribing witnesses.

CLARENCE A. ROUSSEAU.
